COMBINED MEMORANDA AND PENCIL HOLDER

Mauritz C. Ranssen, 3019 Bryant Ave. S.,
Minneapolis, Minn. 55408

Filed Oct. 3, 1972, Ser. No. 294,635

Term of patent 14 years

Int. Cl. D19—99

U.S. Cl. D74—1 C

FIG. 3

FIG. 1

FIG. 4

FIG. 5

FIG. 6

FIG. 2

FIG. 7

FIG. 1 is a perspective view of the combined memoranda and pencil holder showing my new design;

FIG. 2 is a right side elevational view thereof;

FIG. 3 is a front elevational view thereof;

FIG. 4 is a top plan view thereof;

FIG. 5 is a rear elevational view thereof;

FIG. 6 is a bottom plan view thereof; and

FIG. 7 is a right side elevational view of a modified form of the combined memoranda and pencil holder, wherein the terminal flange of the front wall member is angular instead of arcuate.

I claim:

The ornamental design for a combined memoranda and pencil holder, as shown and described.
